UNITED STATES PATENT OFFICE

2,351,612

PRINTING PRESS

John F. Hawley, Riverside, Ill.

Application May 16, 1941, Serial No. 393,717

5 Claims. (Cl. 161—216)

This invention relates to a printing press, and more particularly to a multi-color printing press.

It has heretofore been customary in multi-color printing presses to employ a plurality of form inking rollers having composition surfaces for bringing the ink to the printing plates, which are carried by the printing rolls. It has also been customary to employ metal printing plates in combination with composition form inking rollers.

One of the disadvantages arising from such use of metal printing plates and composition form inking rollers is the relatively short life of the composition form inking rollers and plates. The composition form inking rollers are also relatively sensitive to changes in atmospheric conditions, such as the relative humidity, and do not always give satisfactory results.

According to the present invention, resilient printing plates, preferably of rubber or a rubber composition, are used in place of the former metal printing plates, and metal or other rigid form inking rollers are employed in place of the composition form inking rollers. I find that one or two form inking rollers, or only a few form inking rollers, to each printing press give better results than the larger number of composition form inking rollers heretofore used with each printing roll. Furthermore, the metal form inking rollers have practically an indefinite life of usefulness and are therefore much less expensive in the long run than composition form inking rollers.

It is therefore an important object of this invention to provide a printing press in which the printing rolls carry resilient printing plates, such as plates formed of rubber, rubber composition or the like, and in which the form inking rollers associated with the printing rolls are provided with metal or other rigid surfaces for transferring the ink to the resilient printing plates.

It is a further important object of this invention to provide an arrangement of printing rolls and cooperating form inking rollers wherein the form inking rollers bear directly against the printing rolls and are positively driven by means of gears carried by the printing rolls and form inking rollers.

Another important object of the invention is to provide means for distributing uniform thin layers of ink over the form inking rollers.

This invention (in a preferred form) is illustrated in the drawing and hereinafter more fully described.

On the drawing:

Figure 1 is an end elevational view, with parts 55

broken away, illustrating a printing press embodying the principles of my invention.

Figure 2 is a fragmentary top plan view of the same.

5 As shown on the drawing:

The reference numeral 10 indicates a stationary printing press side frame on which are mounted a plurality of printing rolls 11 journaled at their ends in bearings 12 carried by 10 the side frame 10. On one side of the printing press, the shaft carrying the printing rolls 11 are provided with gears 13, which mesh with other gears 14 on the corresponding ends of the shafts of the usual backing rolls. Idler gears 15 serve to connect the several printing roll gears 13 one with another. The web W of paper is taken off a roll 16 and fed into the printing press in the usual manner.

In the type of printing press shown, which is 20 a three color job, a part of the press is movable into and out of operative position. The movable part is generally indicated by the reference numeral 17 and is provided with a manually operable rack and pinion arrangement 18 for movement along side guide rails 19. Said movable part 17 carries a plurality of form inking rollers 20, which are journaled at their ends in the 25 sidewalls of the press part 17. Instead of three or more form inking rollers to each printing roll,

30 I prefer to employ only two form inking rollers and to provide the driven end of each of the form inking rollers with a gear 21 which meshes with the gear of the corresponding printing roll. The form inking rollers are thus positively 35 driven from the printing rolls which in turn are driven through any suitable train of gears from the main source of power (not shown). When the movable part 17 is in operative position, as illustrated in Figure 1, the form inking 40 rollers 20 are in bearing contact with the printing rolls that they serve.

Each of the printing rolls 11 is provided with 45 raised, annular end bearing rings or flanges 23, which are preferably formed of hardened metal.

The intermediate portion 30 of each roll 11 is 50 cylindrical and carries one or more printing plates 24. The printing plates are preferably formed of flexible resilient material, such as rubber, rubber composition, or a lamination of fabric and rubber composition and are provided on their back with a pressure sensitive adhesive that enables the plates to be properly positioned and secured to the intermediate cylindrical surface of the printing rolls. Each printing plate 24 bears the desired printing indicia 25, the raised

surfaces of which are substantially flush with the surfaces of the annular bearing rings or flanges 23. This is accomplished by making the thickness of the printing plates through the raised printing indicia the same as the height indicated by H, of the raised annular flanges or rings 23 above the cylindrical surface of the printing rolls.

Each of the form inking rollers 20 is made of metal or other rigid material such as stone and is cylindrical throughout its length. Annular end portions 26 may be made of hardened steel for bearing against the annular bearing portions 23 of the printing rolls. Each of the form inking rollers 20 thus presents a rigid surface for contact with the ink receiving surfaces of the printing plates.

Vibrating rolls 32 are used to aid in the uniform distribution of the printing ink on the surface of the form inking rollers 20. These vibrating rolls may be double acting, being actuated by means that include a collar 33 on the shaft of the form inking rollers 20. The collar 33 is provided with a cam groove 34 for guiding a pin 35a in the free end of an arm 35 pivoted at 36 on a lug 37 projecting from the press part 17. Another arm 38 also pivoted at 36 and rigidly connected to the first arm 35 transmits a longitudinally reciprocal movement to the vibrating roll by means of a pin 38a fitting in a circumferential groove 39 in a collar 40 on the shaft of the vibrating roll.

Owing to the fact that the form inking rollers are positively driven from the printing rolls by intermeshing gears 13 and 21, there can be no slippage between the contacting surfaces of the form inking rollers and printing rolls, or between the ink receiving surfaces of the printing indicia on the printing plates and the surfaces of the form inking rollers. The printing plates are built up or otherwise adjusted on the printing roll so that the highs of the printing indicia or the like define a truly cylindrical surface everywhere flush with the surfaces of the flanges 23. When the movable press part 17 is adjusted so that the flanges 23 contact the end portions 26 of the rigid form inking rollers, the surfaces of the latter will barely contact or "kiss" the printing indicia on the printing plate with an accuracy so great that with a 100 line screen, the ink will not go into the depressions on the plate but will remain on the highs. Washing up, which is necessary when conventional rubber or other flexible form inking rollers are employed, is thus eliminated.

For satisfactory results, the printing plate should be adjusted on the printing roll with an accuracy on the order of 0.001 inch. The form inking rollers and the printing roller, including their contacting end surfaces, should be perfectly cylindrical, and the form inking roller should be rigid.

The merely "kissing contact" of the form inking rollers and the printing plate which forms an important feature of the present invention can also be effected by other stop means than the hard bearers shown herein. These bearers need not be made of hardened metal, but may be formed of soft steel, cast iron or the like. Other gear means than those shown may be employed to insure that the form inking rollers have the same surface speeds as the printing plates.

The absence of slipping contact between form inking rollers and printing plates as well as the

absence of pressure on contact therebetween or when impressions are taken results in a much longer life for the plates than was previously realized and also in a more even distribution 5 of the printing ink. The resiliency of the printing plates, of course, diminishes the likelihood of any wear on the printing surfaces or the form inking rollers. Printing plates have double the useful life heretofore expected when employed in the printing press of the present invention.

The vibrating rollers 32 may be formed of glue-glycerine-water compositions well known to the art, or rubber or rubber compositions or other soft and resilient material. A stroke of one inch 15 has been found suitable. The function of the vibrating rollers is to prevent "ghosting," i. e. local faintness of impressions due to some areas of the form inking rollers being supplied with too thin a layer of ink. Such local insufficiencies 20 of ink may occur due to the fact that the form inking rollers are not supplied with an excess of ink which would tend to fill the depressions on the printing plates.

In operation, a web of paper W is fed from the roll 16 through the printing press to receive the successive imprints of ink or color from the several printing plates. The printing plates are positioned in proper registration so as to give the desired multi-colored imprint on the web. 25 The operation of multi-color printing presses is so well known as not to require any further explanation here.

The means and methods according to the present invention are not limited to the preferred examples described hereinabove but include generally a flexible, resilient printing plate coating with a rigid form inking roller and means for maintaining a merely tangential contact between form inking roller and printing plate as well as vibration rolls coating with the form inking roller. The methods of this invention may be broadly characterized as including, in the method of inking a resilient printing plate from a rigid form inking roller, the step of disposing said plate and roller in tangential contact. It is therefore not my intention to limit the patent granted on this invention otherwise than necessitated by the scope of the appended claims.

I claim as my invention:

1. In a printing press, the combination with a printing roll carrying a resilient printing plate and having a rigid annular bearing surface, of a metal form inking roller contacting the raised printing indicia on said plate and bearing directly against said rigid annular bearing surface and of a resilient vibrator roller contacting said metal form inking roller.

2. In combination, a printing roll having rigid bearing surfaces adjacent the ends of said roll and a rigid form inking roller bearing directly against said surfaces together with a resilient vibrator roller contacting said form inking roller.

3. In combination, a printing roll having raised annular hardened rigid bearing surfaces adjacent the ends of said roll and a metal form inking roller bearing directly against said surfaces, together with a resilient roller contacting said metal form inking roller and means for positively vibrating said resilient roller.

4. In combination, a printing roll having rigid bearing surfaces adjacent the ends of said roll, a rigid form inking roller bearing directly against said surfaces, a shaft for said inking roller, a collar having a cam groove affixed to said shaft,

a resilient roller contacting said inking roller, a shaft for said resilient roller, a collar having a circumferential groove affixed to said latter shaft, a frame for supporting said shafts, an arm having one end pivoted from said frame and having at its other end a pin guided by said cam groove, and another arm having one end pivoted from said frame and rigidly connected to the pivoted end of said first arm, said second arm having a pin at its free end seated in the circumferential groove in the collar on the inking roller shaft, said collars and arm coacting to vibrate said resilient roller longitudinally when said inking roller is rotated.

5. In a printing press, apparatus for inking a resilient printing plate comprising a rigid body having a cylindrical surface, means for attaching the reverse face of said plate to said surface, another rigid body having a cylindrical surface adapted to be covered with a film of ink, means for kissingly contacting the highs of said plate while the reverse face of said plate is attached to said first surface, with said second surface adapted to be covered with a film of ink, and a resilient vibrator cylinder contacting said second surface to distribute said film of ink uniformly.

JOHN F. HAWLEY.
